UNITED STATES PATENT OFFICE.

JULIUS PROEGER, OF GREENSBURG, PENNSYLVANIA.

DESIGN FOR THE ORNAMENTATION OF GLASSWARE.

SPECIFICATION forming part of Design No. 21,113, dated October 13, 1891.

Application filed July 10, 1891. Serial No. 399,085. Term of patent 3½ years.

To all whom it may concern:

Be it known that I, JULIUS PROEGER, of Greensburg, in the county of Westmoreland and State of Pennsylvania, have invented a new and original Design for the Ornamentation of Glassware, of which the following is a full, clear, and exact description, reference being had to the accompanying drawings, forming part of this specification, in which—

Figure 1 is a side view of a glass vessel provided with my design. Fig. 2 is an end view of the same, and Fig. 3 is a perspective view of the rosette.

The leading feature of my design for the ornamentation of glassware consists in a rosette formed on the surface of articles of glassware, which rosette is composed of leaves radiating from a common center, spreading in width toward the periphery, and having a bead or button enlargement at their outer ends. The portion of the leaves between the center and the bead enlargement is V shaped in cross-section.

A is the center of the rosette; B, the radiating leaves, and C the bead enlargement. I form one or more of these rosettes on the ar-

ticles of glassware, the rosettes being separated by any desired pattern or design D of cut glassware, the number and position of the rosettes varying according to the size and shape of the vessel to which it is applied.

I claim—

1. A design for the ornamentation of glassware, consisting of a rosette composed of radiating leaves spreading in width toward the periphery and having a bead or button enlargement, substantially as shown and described.

2. A design for the ornamentation of glassware, consisting of a series of rosettes composed of radiating leaves spreading in width toward the periphery and having a bead or button enlargement, and intervening patterns of cut glassware, substantially as shown and described.

In testimony whereof I have hereunto set my hand this 1st day of July, A. D. 1891.

JULIUS PROEGER.
